(57) CLAIM

We claim the ornamental design for a memory card, as shown and described.

DESCRIPTION

FIG. 1 is a front perspective view of a memory card showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is a rear perspective view thereof.

Broken lines and entirely unshaded portions contained within broken lines are not claimed.

The dot dash boundary lines indicate the border at which the claimed portion terminates.

Regarding the terminating boundaries of the unclaimed surface portions of the front and rear of the card, the unclaimed portions terminate immediately preceding the claimed solid line edge.
